UNITED STATES PATENT OFFICE.

IRVING A. KILMER, OF NEW WINDSOR, NEW YORK, ASSIGNOR TO THE KILMER MANUFACTURING COMPANY, OF SAME PLACE.

ROD-ROLLING MILL.

SPECIFICATION forming part of Letters Patent No. 430,998, dated June 24, 1890.

Application filed March 8, 1890. Serial No. 342,357. (No model.)

To all whom it may concern:

Be it known that I, IRVING A. KILMER, a citizen of the United States, residing at New Windsor, in the county of Orange, State of New York, have invented certain new and useful Improvements in Rod-Rolling Mills or Plants, of which the following is a specification, reference being had therein to the accompanying drawings.

10 This invention has relation to a rolling-mill plant for reducing a bloom or billet to a rod by one continuous operation and at a single heat; and the objects and advantages of the invention will appear in the following 15 description, and the novel features thereof will be particularly pointed out in the claims.

Referring to the drawings, Figure 1 is a plan of a plant constructed and arranged in accordance with the invention, and Fig. 2 is 20 a front elevation of the several trains of rolls employed in the plant.

Like letters and numerals refer to like parts in both figures.

The plant comprises four series or trains of 25 rolls, consisting of a billet-train A, a side train B, and a by-lapping pair of rod-trains C and D. The billet-train A has arranged in convenient proximity thereto the bloom or billet furnace A', and consists of a three-high set 30 of rolls A², which are suitably connected and arranged in line with a desired number of co-operating reducing-rolls A³ and A⁴. This train performs its usual function of reducing a billet to a size which adapts it to be operated upon by the rod-train of a mill. The 35 means which are employed in this invention for such a reduction of the reduced billet are what are herein designated as a "side train" B. Any suitable straight guide B' is inter-

40 posed between the billet-train A and the side train B, and a similar guide B² serves to conduct the billet which has been reduced from the side train B to the first set of rolls of the section C of the rod-train proper. The side train is located at such a distance from the billet-train that not only is sufficient room provided for the working of a catcher to return the leading end of the reduced billet to another set of rolls in the billet-train, but to 45 permit of the control by the side train of the slack or surplus, or even in some instances

of the lack of a certain degree of length in the product issuing from the billet-train.

As is usual in rolling-mill plants, the several sections of the plant are run at increased speeds from the billet-train to the rod-train. In this instance separate engines or motors are employed for separate sections of the plant. The engine 1 is geared directly with the side train B, and by means of pulleys and belts with the billet-train A, while the engine 2 is by means of the belts and pulleys shown geared directly with the two sections C D of the rod-train. As is usual in the art, the gearing connecting the engines with the several 65 sections is proportioned so as to give the desired gradual increase of speed in the rolling action of each section progressively from the billet-train.

Now, it will be seen that by placing the 70 side train at a predetermined distance from the billet-train and from the first section C of the rod-train there is opportunity for an overfeed of material from the billet-train to the side train, and from the latter to the first section 75 of the rod-train, and there is also an opportunity of producing a slight stretching of the material in case of an underfeed thereof from either the billet or side train. The occurrence of an underfeed is liable to be somewhat rare, but whenever it exists the result is merely a very slight reduction in the area 80 of the cross-section of the material, which is more advantageous than otherwise to the remaining process of bringing the same to rod 85 size.

The relative arrangement of the several trains is such as to produce alternately cross-sections of square and oval and a final circular cross-section, as indicated in the drawings, 90 and wherever the material emerges from the rolls with a square cross-section curved guides or repeaters E may be employed, and thus the services of a catcher are saved at each of these points in the plant. At other 95 points—that is, where the rod emerges in oval cross-section—catchers are employed to give a rod the usual quarter-turn upon introducing it into the next pair of rolls in a train.

By overlapping the sections C and D of the 100 rod-train a straight guide F may be employed, thereby dispensing with the services of a

catcher at that point, and the further advantage is secured of a contraction of the floor-space required for the plant. It is of course apparent that the number of pairs or sets of 5 rolls in each train may be increased, as desired, to produce a desired reduction of a billet, or, in other words, to effect the production of a rod of a desired size.

Heretofore there have been different arrangements of billet and rod trains with or without the interposition of an intermediate train arranged between the billet and rod train and in feed-line with both—that is, so that the last rolls of one train would feed directly into the first rolls of a subsequent train in the plant, and heretofore, also, a system of rolls having the several functions of billet and rod-reducing rolls have been arranged to conjointly and continuously operate to produce rods from billets; but I am not aware of an arrangement which simultaneously and in the manner hereinbefore described provides for an overfeed or an underfeed, and for the same reduction in the number of catchers required to operate the plant, as is provided in the invention herein set forth.

What is claimed is—

1. A plant for rolling billets to rods, comprising a billet-train, a side train arranged at 30 a distance therefrom and overlapping at one end only, and an intermediate rod-train in overlapping sections, substantially as described.
2. In a rod-mill plant, a billet-train, a side train arranged at a distance therefrom and overlapping the same, and an intermediate rod-train in sections, having overlapping terminals, with one end of the train overlapping the side train, substantially as described.
3. In a rod-mill plant, a billet-train, a side train, and an intermediate rod-train with one 40 terminal overlapping the side train and the

other terminal outside the limit thereof, substantially as described.

4. In a rod-mill plant, a billet-train having 45 supplemental reducing-rolls, a side train overlapping the same and arranged at a distance therefrom, and a rod-train in overlapping sections with both sections between the billet and side train, with one terminal overlapping the side train, substantially as described. 50

5. In a rod-mill plant, a billet-train, a side train arranged at a distance therefrom, a straight guide between the two, an intermediate rod-train in overlapping sections with 55 one terminal overlapping the terminal of the side train, and a straight guide from the side train to the nearest overlapping terminal of the rod-train, substantially as described.

6. In a rod-mill plant, a billet-train, an 60 overlapping side train arranged at a distance from the billet-train, an overlapping section of a rod-train, arranged at a distance from said side train and nearer the billet-train, and an overlapping final section of a rod-train, arranged 65 near its first section, and means for rotating the billet, side, and sectional rod trains at progressively increased velocities, substantially as specified.

7. In a rod-mill plant, a billet-train, a side 70 train arranged at a distance therefrom and overlapping the same, and an intermediate rod-train in overlapping sections, with the first section nearest the billet-train and overlapping the side train, and the final section 75 outside the limit of the side train, substantially as described.

In testimony whereof I affix my signature in presence of two witnesses.

IRVING A. KILMER.
